(57) **CLAIM**

I claim, the ornamental design for an exercise apparatus, as shown and described.

DESCRIPTION

FIG. 1 is a front and side perspective view, of the exercise apparatus with handles shown in a first position; and, FIG. 2 is a front and side perspective view of the exercise apparatus of FIG. 1 but with the handles shown in a second position and the exercise apparatus in a different orientation than shown in FIG. 1.

1 Claim, 2 Drawing Sheets

FIG. 2

UNITED STATES PATENT AND TRADEMARK OFFICE
CERTIFICATE OF CORRECTION

PATENT NO. : Des. 525,668 S
APPLICATION NO. : 29/210053
DATED : July 25, 2006
INVENTOR(S) : Clive Anthony Payne

Page 1 of 1

It is certified that error appears in the above-identified patent and that said Letters Patent is hereby corrected as shown below:

On the "Title Page", item (76) should read --Clive Anthony Payne, 93 Carbery Avenue, Southbourne, Bournemouth, BH6 3LP, (GB)--.

Signed and Sealed this

Tenth Day of April, 2007

A handwritten signature in black ink, appearing to read "Jon W. Dudas". The signature is written in a cursive style with a large, stylized 'J' at the beginning.
